RAILWAY SWITCH OPERATING APPARATUS

Morgan A. Nyberg, Milwaukee, Wis., assignor to
The Union Switch and Signal Company, Swiss-
vale, Pa., a corporation of Pennsylvania

Application October 23, 1943, Serial No. 507,357

7 Claims. (Cl. 246—291)

My invention relates to railway switch operating apparatus, and particularly to apparatus of the type which includes a hand lever for throwing a spring switch.

One object of my invention is the provision in apparatus of the type described of means for preventing the hand lever from being thrown to either extreme position unless the switch points move to the corresponding extreme position.

Another object of my invention is to prevent the possibility of the hand lever from being jerked out of an operator's hands if he attempts to reverse the switch when the spring which biases the points to their set positions is compressed beyond its normal compression due for example to the presence of an obstruction which prevents the switch points from assuming the extreme position corresponding to the position of the hand lever.

According to my invention, I attach two bars to the normally closed point in parallel spaced relation. These bars extend underneath the one stock rail adjacent to the switch operating mechanism and are provided at their free ends with upstanding arms which are threaded to receive adjustable bolts. The parts are so adjusted and so proportioned that the hand throw lever of the switch operating mechanism can only be moved to or away from its normal position past the one bolt when the switch points occupy their full normal positions, and that the hand throw lever can only be moved to or away from its reverse position past the other bolt when the switch points occupy their full reverse positions.

Other objects and characteristic features of my invention will become apparent as the description proceeds.

I shall describe one form of apparatus embodying my invention, and shall then point out the novel features thereof in claims.

In the accompanying drawing, Fig. 1 is a top plan view partly cross sectioned showing a spring switch provided with one form of switch operating apparatus embodying my invention. Fig. 2 is an end view of the apparatus shown in Fig. 1. Fig. 3 is a sectional view taken on the lines III—III of Fig. 1. Fig. 4 is a detail view showing in isometric projection on an enlarged scale a portion of the apparatus shown in Figs. 1 and 2.

Similar reference characters refer to similar parts in each of the several views.

Referring to the drawings, the reference character A designates a railway switch comprising as usual two fixed rails 1 and 1a and two movable rails or switch points 2 and 2a. The movable

rails are fastened together by a front rod 5 and a head rod 6, and may be moved into a normal or a reverse position by means of a switch operating mechanism B which is connected with the head rod 6 through the medium of a link 9 and a spring connecting rod C. When the switch occupies its normal position in which it is shown in Fig. 1, the movable rail 2a engages the fixed rail 1a and the movable rail 2 is spaced a slight distance from the fixed rail 1. When the switch is reversed, however, the movable rail 2 then engages the fixed rail 1, and the movable rail 2a is spaced from the fixed rail 1a.

The switch operating mechanism B may be of any suitable type, but as here shown, it comprises a switch stand 10 having its base 10a spiked or otherwise secured to the ties adjacent to the switch A. A gear shaft 11 is journaled in the switch stand 10 and carries a crank 11a and a gear segment 12. The crank 11a of the switch stand B is pivotally connected to one end of the link 9, while the gear segment 12 meshes with a pinion gear 13 keyed to a pinion shaft 20. The pinion shaft 20 extends through the side of the switch stand 10, and has attached to its outer end the usual weighted switch throwing lever 21.

The spring connecting rod C may have any suitable form, but in the well known form here shown, this connecting rod comprises a cylindrical housing 14 having a lateral extension 14a fastened to the head rod 6. The left-hand end 14b of the housing 14 has a smaller diameter than the body of the housing, while the right-hand end is threaded to receive a cap 15 having an end 15a similar to the end 14b. Slidably mounted in the opening in the end 14b is a sleeve 16 provided with an annular flange 16a located within the housing 14, and similarly mounted in the opening in the end 15a in a sleeve 17 provided with an annular flange 17a located within the housing 14. A spring rod 18 extends through both sleeves 16 and 17 with sufficient clearance to permit the rod to slide freely in the sleeves and this rod carries a compression spring 19 which engages the sleeves at the annular flanges, and urges the sleeves toward the positions in which the annular flange 16a of the sleeve 16 engages the shoulder formed on the inner side of the housing 14 by the end 14b, and the annular flange of the sleeve 17 engages the shoulder formed on the inside of the cap 15 by the end 15a. The spring rod 18 is provided with an annular shoulder 18a for at times engaging the outer end of the sleeve 17, and with a nut 18b for at times engaging the outer end of the sleeve 16. The spring rod 18 is also provided with

a nut 18c for locking the nut 18b in an adjusted position. The right-hand end of the spring rod 18 is pivotally attached to the link 11.

The portion of the apparatus thus far described is well known, and its operation is as follows: As shown in the drawing, both the switch A and the switch operating mechanism B occupy their normal positions, and the parts are so proportioned that under these conditions a force will be transmitted to the switch points 2 and 2a through the medium of the link 11, spring rod 18, nut 18b, sleeve 16, spring 19, sleeve 17, housing 14 and head rod 6, which force will cause the spring 19 to become compressed and yieldably urge the switch points to their normal positions.

When the switch points occupy their normal positions as shown and it is desired to reverse them, the switch throwing lever 21 is rotated from the position shown through an angle of 180° in a counterclockwise direction, thereby rotating gear segment 12 and crank 11a in the same direction and hence moving link 9 and spring rod 18 toward the left. The motion of the spring rod 18 toward the left causes a force to be exerted on the switch points 2 and 2a through the medium of the shoulder 18a, sleeve 17, spring 19, sleeve 16, housing 14, and head rod 6 which force moves the points to their reverse positions. The parts are so proportioned that when the switch points reach their full reverse positions the spring 20 will become compressed beyond its initial compression and will then exert a force on the points which yieldably holds them in their reverse positions.

If, after the switch points have been moved to their reverse positions in the manner just described, it is desired to restore them to their normal positions, this may be done by restoring the lever 21 to the position shown. The subsequent movements of the parts under these conditions is just the reverse of that described above, and will be apparent from the drawing without further description.

When the parts occupy the positions shown and a train trails the switch the wheels of the train exert a force on the closed switch point 2a which force causes the points to move over laterally in opposition to the bias of the spring 19, and as soon as the train clears the switch, the spring 19 acts to return the points to the positions shown in the drawing.

With the apparatus constructed in the manner thus far described it is possible for a trainman to force the switch throwing lever 21 to its full normal or full reverse position even though the switch points are prevented from moving to the corresponding extreme position due to some obstruction such for example, as a lump of coal, snow and ice, or the like, and derailments have been reported due to a train moving over a spring switch on a hand signal under such a condition.

Moreover, with the switch A arranged to be operated in the manner described it sometimes happens that a train which has started to trail the switch stops for one reason or another in a position in which the switch points are held in their trailed positions by the wheels of one of the vehicles of the train, and that while the points are then held in their trailed positions, a trainman attempts to reverse the switch by means of the switch throwing lever 21. When this happens, the operation of the mechanism releases the energy stored in the compressed spring of the spring connecting rod C, and causes this energy to be transmitted back through the spring

rod 18, link 9, gear segment 12, bevel gear 13 and shaft 20 to the lever 21, with the result that there is a tendency to jerk the lever 21 out of the trainman's hand.

It is desirable to prevent this and the other condition described above from happening to guard against possible injury to the trainman, or derailment of the train, as the case may be, and to this end, I provide the apparatus forming the subject matter of my present invention, which apparatus I shall now describe.

As here shown, this apparatus comprises two bars 25 and 30 which extend underneath the fixed rail 1a in parallel spaced relation and are secured at one end to the normally closed switch point 2a. These bars are slidably supported intermediate their ends by suitable guides 41 here shown as secured to the nearest tie, and are provided at their free ends with upstanding arms 25a and 30a, respectively, which arms are screw threaded to receive adjustable bolts 31 and 32, respectively. Mounted on the free end of each bolt is a removable tubular extension 31a or 32a which is normally held in a fixed position relative to the associated bolt by means of a pin 33. This pin passes through clearance holes in the bolt and tubular extension and is drilled at its lower end for the reception of a wire seal 34 which must be broken in order to enable the tubular extension to be removed, for a purpose which will appear presently, and which when removed leaves a telltale of its removal for a purpose which will also appear presently.

The parts are so proportioned and bolts 31 and 32 are so adjusted that the tubular extension 32a on the bolt 32 will project into the path of movement of the lever 21 to or away from its normal position except when the switch points are in their full normal positions, and that the tubular extension 31a on the bolt 31 will project into the path of movement of the lever 21 to or away from the reverse position except when the switch points occupy their full reverse positions.

It will be seen, therefore, that when the switch throwing lever 21 is operated from its normal position toward its reverse position to move the switch points to their reverse positions if they are prevented from moving to their full reverse positions for any reason, such as would be the case, for example, if a lump of coal or some other obstruction became lodged between the stock rail 1a and the switch point 2a, the tubular extension 31a on the bolt 31 will project into the path of movement of the lever 21 and will thus prevent it from being moved to its full reverse position. When this happens, the trainman will be made aware of the presence of the obstruction and will remove it, or will at least return the lever to its normal position, thereby avoiding any possibility of a derailment due to a train moving over the switch with the switch points displaced from their full reverse positions.

Similarly, when the switch throwing lever 21 is operated from its reverse position toward its normal position to move the switch points to their normal position, the tubular extension 32a on the bolt 32 will prevent the lever 21 from being moved to its full normal position unless the switch points move to their full normal positions in response to the movement of the lever.

If the switch points are displaced from their normal positions for any reason when the lever 21 occupies its normal position, the tubular extension 32a will then overlie the lever, and will

thus prevent the operator from moving the lever away from its normal position without first removing the extension 32a. This can only be done by removing the wire seal 34 and associated pin 33 and then slipping the extension 32a off the bolt 32, and it is assumed that if the trainman does this he will then take proper precautions when he moves the lever away from its normal position to prevent the lever from accelerating rapidly due to the abnormally high spring force which then exists in the spring 19 as a result of the displacement of the points from their normal positions. Such abnormal operation of the lever might be necessary, for example, if a train which has stopped for some reason while trailing the switch desires to back up to take up slack preparatory to making a new start. The fact that the trainman has to break the wire seal in order to operate the lever under the conditions just described provides a telltale of the abnormal operation of the lever, and insures that the trainman will report such operation.

The tubular extension 31a on the bolt 31 functions in a similar manner to prevent a trainman from operating the switch points to their normal positions when they are displaced from their reverse positions without first taking proper precautions to avoid possible injury from rapid acceleration of the lever caused by the extra compression of spring 19, this rapid acceleration of the lever generally being referred to in the art as a "flying lever."

Some advantages of apparatus embodying my invention are that it is simple in construction, relatively inexpensive to manufacture, and can be readily added to almost any type of spring switch layout without necessitating any changes in the apparatus.

Although I have herein shown and described only one form of apparatus embodying my invention, it is understood that various changes and modifications may be made therein within the scope of the appended claims without departing from the spirit and scope of my invention.

Having thus described my invention, what I claim is:

1. The combination with a switch and a manually operable lever movable between two extreme positions and operatively connected with said switch through resilient means for moving said switch between its two extreme positions, of means secured to one of the movable points of said switch and cooperating with said lever to prevent movement of said lever to or away from its one extreme position unless the switch points occupy positions in agreement with the position of said lever.

2. The combination with a switch and a manually operable lever movable between two extreme positions and operatively connected with said switch through resilient means for moving said switch between its two extreme positions, of means secured to one of the movable points of said switch and cooperating with said lever to prevent movement of said lever to or away from either extreme position unless the switch points occupy positions in agreement with the position of said lever.

3. The combination with a switch and a manually operable lever rotatable between two extreme positions and operatively connected with said switch through resilient means for moving said switch between corresponding extreme positions, of a member secured to one of the switch

points and provided with means which projects into the path of movement of said lever to or away from one of its extreme positions except when said switch occupies its corresponding extreme position.

4. The combination with a switch and a manually operable lever rotatable between two extreme positions and operatively connected with said switch through resilient means for moving said switch between corresponding extreme positions, of two members secured to the switch points in parallel spaced relation to move therewith, means secured to the one member in such position that it will project into the path of movement of said lever to or away from its one extreme position except when said switch occupies its corresponding extreme position, and other means secured to the other member in such position that it will project into the path of movement of said lever to or away from its other extreme position except when said switch occupies its corresponding extreme position.

5. The combination with a switch and a manually operable lever rotatable between two extreme positions and operatively connected with said switch through resilient means for moving said switch between corresponding extreme positions, of two members secured to the switch points in parallel spaced relation to move therewith, means removably secured to the one member in such position that it will project into the path of movement of said lever to or away from its one extreme position except when said switch occupies its corresponding extreme position, and other means removably secured to the other member in such position that it will project into the path of movement of said lever to or away from its other extreme position except when said switch occupies its corresponding extreme position.

6. In combination, a railway switch, an operating mechanism provided with a manually operable lever movable between two extreme positions, spring means connecting said mechanism with said switch in such manner that the switch will be biased to an extreme position corresponding to the extreme position of said lever, two rods secured to said switch for movement therewith on opposite sides of the vertical plane passing through the pivotal axis of said manually operable lever and each provided at its free end with an upstanding portion having a screw threaded hole, two bolts one adjustably screwed into each of said holes and each cooperating with said lever, the parts being so proportioned and adjusted that the one bolt will project into the path of movement of said lever toward or away from its one extreme position except when the switch points are in their corresponding extreme positions and that the other bolt will project into the path of movement of said lever toward or away from its other extreme position except when the switch points are in their corresponding extreme positions.

7. In combination, a railway switch, an operating mechanism provided with a manually operable lever movable between two extreme positions, spring means connecting said mechanism with said switch in such manner that the switch will be biased to an extreme position corresponding to the extreme position of said lever, two rods secured to said switch for movement therewith on opposite sides of the vertical plane passing through the pivotal axis of said manually operable lever and each provided at its free end with

an upstanding portion having a screw threaded hole, two bolts one adjustably screwed into each of said holes, and two tubular extensions one removably secured to each bolt, the parts being so proportioned and adjusted that the one extension will project into the path of movement of said lever toward or away from its one extreme position except when the switch points

occupy the corresponding extreme positions and that the other extension will project into the path of movement of said lever toward or away from its other extreme position except when the switch points occupy their corresponding extreme positions.

MORGAN A. NYBERG.
